The ornamental design for a currency dispensing machine, as shown and described.

DESCRIPTION

FIG. 1 is a perspective view of a currency dispensing machine showing our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings represent portions of the currency dispensing machine that form no part of the claimed design. The half-circular line pattern shown in FIGS. 1, 2, 4, 5 and 7 form no part of the claimed design.
